UNITED STATES PATENT OFFICE.

EDWARD ALFRED GRAHAM, OF BROCKLEY, LONDON, ENGLAND; MARIA GRAHAM AND ALFRED GRAHAM EXECUTORS OF SAID EDWARD ALFRED GRAHAM, DECEASED.

TELEPHONE RECEIVER WITH DETACHABLE SOUND AMPLIFIER.

Application filed February 12, 1926, Serial No. 87,899, and in Great Britain September 11, 1925.

This invention relates to means of the kind in which a sound amplifier surmounts a hollow base, pedestal or plinth containing a wireless telephonic receiver, and it has for 5 its object to provide for the better and simpler connection together of the said parts, the receiver being so constructed or constituted that, if desired, it can readily be attached, after removal from the base, pedestal 10 or plinth (hereinafter referred to as the base), to another sound amplifier, say the tone arm or sound conduit of a gramophone for example.

To this end, the face of the telephonic receiver which abuts against the inner or lower side of the top wall of the base is formed or provided with an externally screw threaded member or stem adapted to pass through an opening in the top wall of the base and 15 to project well above such top wall so that it can enter a companion internally screw threaded and non-sonorous bushing portion of a horn or trumpet of any suitable description (hereinafter referred to as the horn) which bears on the top of the base. In this way, the horn is directly made use 20 of to clamp the top wall of the base directly between it and the telephonic receiver, the act of unscrewing the horn serving to release the parts without it being necessary to 25 manipulate any auxiliary fastening device.

The internally screw threaded bushing with which the narrower end of the horn is equipped may be made of rubber or like 30 vibration-deadening or non-sonorous material.

The accompanying illustrative drawing shows partly in side elevation and partly in vertical section, a combined sound amplifier, hollow base and telephonic receiver connected together according to the invention.

a is a hollow base, *b* a sound amplifier in the form of an upwardly extending horn having its smaller lower end fitted with an 35 internally screw threaded bushing *b*¹ of rubber and bearing on the top wall *a*¹ of the base *a*, and *c* a telephonic receiver having an upwardly extending externally screw threaded tubular member or stem *c*¹ that extends 40 through a hole *a*² in the top wall *a*¹ of the base *a* and is firmly engaged with the internally screw threaded bushing *b*¹ in the lower 45 end of the horn *b*. In this way the top

wall *a*¹ of the base *a* can be firmly clamped directly between the smaller end of the horn 55 and the upper end of the telephonic receiver *c* but in such a manner that the horn and telephonic receiver can readily be disengaged from one another and from the base *a* when 60 it is desired to do this.

A telephonic receiver *c* formed or provided with an externally screw threaded member or stem *c*¹ such as referred to, will be found especially suitable for connection, after removal from the horn *b* and base *a* 65 to any alternative sound amplifying conduit, such for instance, as the tone arm of say a gramophone, a more or less flexible member being employed to effect the connection and taking the place of the screw 70 threaded bushing *b*¹.

The horn *b* may be made in two parts, adapted to be screwed together with an interposed ring *k* of rubber or like material.

What I claim is:—

1. Sound amplifying means embodying a telephonic receiver, comprising a hollow base, a telephonic receiver having an externally screw threaded hollow stem extending through a hole in the top wall of said base 80 and extending above said wall and a horn having its smaller inlet end fitted with a bushing of vibration deadening or non-sonorous material formed with an internal screw threaded companion to the external 85 screw thread on the stem of the telephonic receiver and firmly engaged with such stem whereby the top wall of the base is firmly clamped between the upper end of the receiver and the smaller end of the horn in a 90 readily detachable manner.

2. Sound amplifying means embodying a telephonic receiver, comprising a hollow base having a flat top wall, a telephonic receiver having at one end an externally screw 95 threaded hollow stem extending through a hole in said top wall and extending above the same and a horn, the smaller inlet end of which is fitted with an internally screw threaded bushing of india rubber, firmly engaged with said screw threaded stem and bearing directly against the top wall of said base.

Signed at London, England, this eleventh day of January, 1926.

EDWARD ALFRED GRAHAM.
